LENGTH ADJUSTING AND ATTACHING
BRACKET

Martin L. Samuels, Chicago, Ill., assignor to Reflector Hardware Corporation, Chicago, Ill., a corporation of Illinois

Application March 12, 1948, Serial No. 14,403

2 Claims. (Cl. 248—224)

1

This invention relates to improvements in devices for supporting merchandise for display purposes and is particularly concerned with means for adjusting the length of a bar-like supporting member so that its attaching means may be made to register with complementary means on a pair of spaced upright standards, which standards may be fixed in spaced relation by having their bottoms secured to a floor or table. The supporting member or cross-bar, in turn supports a plurality of hanger-brackets on which the merchandise is hung, and thus the cross bar is submitted to a considerable load. It is therefore an object herein to provide strong means for connecting the length-adjusting means to the standard.

The standards herein are provided either with one vertically aligned row or with two vertically aligned rows of openings, in the form of slots vertically aligned and spaced. The supporting members or cross bars are generally provided with attaching means designed to register with and enter the slots and interlock therewith to secure the cross support to the standards. However, due to variations in the spacing between the standards proper registration of the projections with the slots is not always possible. This is a troublesome matter, which it is an object of this invention to overcome.

I overcame this difficulty by providing a bracket having fastening devices thereon which cooperate with the slots to secure the bracket and further provide the bracket with means to slidably receive one end of the cross support so that the bracket can be moved in relation to the cross support, or the cross support can be moved in relation to the bracket, and I also provide means operable after adjustment to clamp the bar and bracket together.

Objects of the invention are; to provide an attaching bracket for adjusting the length of a cross-support; to provide an attaching bracket which can be adjusted on and clamped to a cross-bar; to provide means for clamping the bracket and bar after adjustment of the bracket thereon; to provide a bracket which can be formed chiefly from sheet material; to provide means for strongly resisting lateral motions of the bracket at its points of attachment with the standard; to provide an elongated thrust surface at a point below the lower of the two attaching hooks; to so locate the cross-bar in relation to its attaching hooks and said thrust surface as to substantially improve the hook-supporting ability of hooks and bracket; to provide a load-supporting structure which can be attached by using one bracket instead of two brackets; to provide right and left hand brackets to be used at opposite ends of a cross-bar; and to provide strong and inexpensive means for the adjusting and attaching purposes herein.

2

Objects, features and advantages of the invention will be pointed out in the description of the drawings and in said drawings:

Fig. 1 is a front view showing the invention applied in the support of both ends of a crossbar in relation to two standards;

Fig. 2 is a vertical cross section taken approximately on line 2—2 of Fig. 1;

Fig. 3 is a detailed front view of the right hand bracket of Fig. 1;

Fig. 4 is a plan section taken approximately on line 4—4 of Fig. 3;

Fig. 5 is a modification showing a bar supported only by one bracket of this invention instead of two; and

Fig. 6 is a plan section taken on line 6—6 of Fig. 5 showing the construction of that end of the bar which does not have a bracket.

Referring to the drawings, numeral 1 and 2 respectively indicate two standards each having a vertical row of slots 3 with which hooks of a bracket herein are adapted to interlock. Numeral 4 indicates a crossbar which is adapted to support a series of detachable hanger brackets 6. Each of these hanger brackets has a horizontally projecting rod 7 adapted to support goods to be displayed. The bar is therefore submitted to a considerable load, and it is important to provide means by which the bar can be strongly attached to the standards.

The cross-bar 4 has each end inserted and slidably guided in an extension bracket and attaching structure of this invention.

The brackets are made as rights and lefts but are otherwise structurally identical. Now referring to Figs. 2, 3, and 4, the bracket is formed from a piece of sheet metal bent to provide first and second right angularly related portions adapted to lie in a vertical plane when the bracket is attached to a standard or support. The first plate-like portion is indicated at 10 and the second portion is indicated at 11. The first portion is provided with a pair of marginally rearwardly extending upper and lower hook structures respectively indicated at 14 and 15. The hooks are arranged vertically one above the other, and each hook has a downwardly faced edge surface 16 adapted to flatly engage the upper edge surface of the slot with which it is associated. Each hook also has an edge surface 17 adapted to flatly engage the rear surface of the wall of the standard. The plate 10 is provided with two punched out portions or prongs respectively indicated at 19 and 20, each portion being bent laterally in an opposite direction as best shown in Figs. 3 and 4. Each punched out prong or portion is provided with an edge surface 21 (see Figs. 2 and 4), which flatly engages the front face of the standard when the hooks are interlocked in the slots.

The upper end of the punched out portion 20 and the lower end of the punched out portion 19 may be said to lie in a horizontal plane which is intermediate of and substantially midway between the planes of edge portions 16 of the hook structure, while the bodies of the prongs or portions 19 and 20 are disposed in separate planes substantially at right angles to the plane of the forward face of the standard. These elements 19 and 20 (see Fig. 4) serve to strongly resist lateral swinging motion of the bracket about its points of connection with the standard, for forces tending to swing the bracket are absorbed by the prongs or portions 19 and 20 in edge compression. Thus, the prongs or portions 19 and 20 will absorb far greater bracket swinging forces than would be the case if the prongs were arranged so as to absorb these forces in simple bending moment applied thereto.

The plate-like portion 11 of the bracket has upper and lower bent-over portions 25 which form a guide in which the end of the bar 4 can slide. The portion 11 is provided with a slot 26 which extends in a direction arranged longitudinally of the bar, that is horizontally, when the bar is attached. Through this slot is passed a bolt 27, the outer end of the bolt being threaded and the wing nut 28 being engaged therewith. The head 29 of the bolt engages the outer surface of the portion 11 as shown in Fig. 2 and by means of the wing nut the parts can be clamped in any position to which they may have been adjusted. This clamping action is, of course, performed after the hooks have been interlocked with the slots.

The height relations of the portions 10 and 11 of the bracket to one another and to the hooks and elements 19 and 20 are important.

It is to be noted that the vertical height of the plate portion 10 is substantially greater than the vertical height of the plate portion 11 and that the plate portion 11 is so related to the plate portion 10 as to provide a substantial extension of the portion 10 below the bottom of the portion 11. This downwardly extending portion is also at a level below the lower hook 15 and is provided with a surface 30 which is co-planar with surfaces 21 and which engages the front face of the standard as shown when the bracket is attached. The portion 11 is disposed in horizontal opposition to the hook structure, but the plate 10 extends a substantial distance below the lower side of portion 11. The top of the bar 4 is about at the level of the surface 16 of the upper hook and is a substantial distance above the level of the surface 30, so that unusually strong supporting action is obtained by the bracket. This arrangement together with the arrangement of the elements 19 and 20 and surface engagements at 21 and 30 result in a very rigid locking connection.

In Fig. 5 a modification has been shown in which only a single bracket like that previously described is used, at one end of a bar 32. The bracket in this case has exactly the same construction as that previously described. However, the opposite end of the bar 32 is modified by bending its end 33 to the right angular position shown, and by securing to the inner side of this portion 33 a plate 34 which has the same construction as plate portion 10 previously described, in regard to its hook construction. The plate 34 is suitably secured to the extension 33 as by welding and has substantially the same relation to the extension 33 as the plate 10 has to the plate portion 11 in the previously described structure.

In this form of the invention the hook structure 34 is first attached in the slots, and then the bracket is adjusted to obtain interlocking of its hook structure with the slots, and then the wing nut is manipulated to clamp the parts together.

Although I am aware that adjustments of this general kind have been provided for, I do not believe that any structure comparable to that shown herein has ever been provided which carries projections which interlock with slots of uprights, and in which the supporting and interlocking elements cooperate to obtain that degree of supporting strength obtained by the practice of this invention.

I claim:

1. A bracket adapted to be supported in outstanding relation with the forward face of a standard which has a row of vertically aligned and spaced slots therein comprising, a piece of sheet metal bent to provide first and second right angularly plate-like portions adapted to lie in vertical planes when the bracket is attached to the standard, the first portion having upper and lower marginal hooks adapted to interlock with corresponding slots of the standard, the second portion having means to slidably receive and guide and support the end of a crossbar, means for clamping the bracket to the bar, said first portion having struck out therefrom in opposite directions prongs disposed in separate planes substantially at right angles to the plane of the forward face of the standard and having edges adapted to engage said forward face to resist lateral swinging motion of the bracket in relation to the standard, the vertical height of the first portion being substantially greater than that of the second portion and having a part extending a substantial distance below the lower hook and which is adapted to abut the standard.

2. A bracket entirely formed from a single piece of sheet material such as metal having a vertical plate-like body having two opposite face surfaces said body having at its rear two hooks, adapted to interlock with vertically aligned slots of a standard, when the bracket is moved downwardly, and said body having at its rear a vertical transversely narrow edge surface adapted to fit tightly against the front face of the standard when the hooks are fully engaged, contiguous portions of said body being punched out in opposite directions to adapt portions of said narrow edge surfaces to act to brace the body of the bracket against swinging motion about said rear edge surface, the front of said bracket having a right angularly related horizontal portion having a recess on its rear side adapted to slidably receive the end of a bar, and said portion having a slot for receiving a releasable fastening device by which the bar can be clamped to said portion.

MARTIN L. SAMUELS.
